Inventor:
Edgar A. Monfort.

By James L. Norris, Atty.

UNITED STATES PATENT OFFICE.

EDGAR A. MONFORT, OF NEW YORK, N. Y.

CARTRIDGE.

SPECIFICATION forming part of Letters Patent No. 276,451, dated April 24, 1883.

Application filed July 5, 1882. (No model.)

To all whom it may concern:

Be it known that I, EDGAR A. MONFORT, a citizen of the United States, residing at New York, in the county and State of New York, 5 have invented new and useful Improvements in Cartridges for Fire-Arms, of which the following is a specification.

This invention relates to improvements in cartridges for fire-arms, and has for its object 10 to provide an improved cartridge of such construction that it can be used in a fire-arm having means for generating a current of electricity which serves to ignite the charge in the cartridge.

15 The invention consists in a cartridge having within its base two or more platinum wires crossing each other, and having terminals formed of the same or of different wire projecting through the base, and having an insulated support therein.

Figure 1 represents a sectional view of the improved cartridge placed in the barrel of a fire-arm which is provided with means to ignite the charge by a current or spark of electricity; Fig. 2, an end view of the breech of the gun, showing the conducting-plates with which the platinum points of the cartridge come in contact. Fig. 3 is a perspective view of the cartridge, part of the case being broken 25 away to show the arrangement of the platinum wire or wires within the shell.

A in the drawings indicates the breech-piece of the arm, which may be made of any convenient form. Within this breech is placed a 30 storage or other battery, B, of any suitable type. It may, for instance, be a generator of electric energy; but in the present state of the art it is preferable to use a storage-battery or accumulator of any of the well-known varieties. To the poles of said battery are connected conducting-wires C C', which are united 35 at their lower ends to conducting plates or disks a a, set in the breech-plate, said plate being composed of india-rubber, celluloid, or other non-conducting material. One of the wires, as C, is cut at a suitable point and provided with connection-points c c', which are normally separated so as to break the circuit.

To one of said connection-points, c', a key or 40 push-button, D, or any other suitable device,

may be connected, by operating which the circuit may be completed.

E indicates the barrel of the arm, which is of the usual construction of breech-loaders.

F, Fig. 3, indicates my improved cartridge, 55 having in its base a non-conducting disk, G. This disk forms a support for the terminals of two or more fine platinum or other wires, I I, arranged at or about at right angles with each other within the shell, and in contact with 60 each other at their point of intersection. The points d d d d of these wires project rearward from the base of said cartridge, being supported, as already mentioned, by the non-conducting disk G. The powder K occupies the 65 usual proportion of the shell, lying upon the base and upon all sides of the intersecting wires I I. When the cartridge F is placed in the barrel and the barrel turned down into its seat, the points of at least two of these wires 70 will be in contact with the conducting-surfaces a a in the breech-plate. If now the key D is operated and the circuit closed, electricity will flow from the battery through the platinum or other wire or wires I, thereby heating the latter to a red heat and igniting the charge. This characteristic of platinum of offering such resistance to the passage of a current as to be heated to a red or even white heat almost instantaneously is too familiar to require mention. By using two or more wires which cross at a common point within the shell ignition is effected at several different and equidistant points, the powder being fired next the base 75 and burning toward the ball. 80

I do not here claim the fire-arm having the means shown and described for producing currents of electricity to ignite the charge in my improved cartridge; nor do I limit myself to the use of the cartridge in the particular fire-arm shown; but 85

What I claim is—

1. A cartridge provided within its base with two or more wires crossing each other and their terminals projecting through the base of 90 the shell, and having an insulated support therein, substantially as described.

2. A cartridge having within its base two or more than two platinum wires crossing each other at a common point, and having termi- 100

nals formed of the same or of different wire projecting through the base, and having an insulated support therein, substantially as described.

5 3. The cartridge F, having the platinum wires I I crossing each other within the base, and provided with an insulating-support set in said base, from which the points of said wires project, substantially as described.

In testimony whereof I have hereunto set my hand in the presence of two subscribing witnesses.

EDGAR A. MONFORT.
